COMBINED VIEWER AND CAMERA ATTACHMENT FOR A CATHODE RAY OSCILLOSCOPE

Maurice J. Merrick, Portland, Oreg., assignor to Tektronix, Inc., Beaverton, Oreg., a corporation of Oregon

Filed Dec. 27, 1960, Ser. No. 63,349

Term of patent 14 years

(Cl. D61—1)

Fig. 1

Fig. 2

Fig. 3

Fig. 4

FIG. 1 is a perspective view of a combined viewer and camera attachment for a cathode ray oscilloscope showing my new design;

FIG. 2 is a partial vertical section through the central portion thereof looking toward the right in FIG. 1;

FIG. 3 is a perspective view thereof opposite that shown in FIG. 1; and

FIG. 4 is a partial vertical section through the central portion thereof looking toward the right in FIG. 3.

The broken line showing is for illustrative purposes only.

I claim:

The ornamental design for a combined viewer and camera attachment for a cathode ray oscilloscope, as shown and described.
